ELECTRODE HOLDER

Ford S. Miller, Lancaster, N. H., assignor to M. L.
B. Manufacturing Company, Hollywood, Calif.,
a corporation of California

Application September 29, 1941, Serial No. 412,698

6 Claims. (Cl. 219—8)

This invention relates to devices for manually supporting welding electrodes during electric welding. Such devices perform the dual purpose of mechanically supporting the electrode, and also completing electrical connection thereto.

An object of the invention is to provide a convenient and rapidly operated electrode holder.

Another object is to provide an electrode holder in which the current-carrying parts are thoroughly electrically insulated to prevent injury to the operator from flashes and arcs.

Another object is to provide a particularly simple and speedy locking mechanism for locking an electrode in the holder.

Other more specific objects and features of the invention will become apparent from the detailed description to follow, which refers to the drawing of a particular embodiment of the invention.

In the drawing:

Fig. 1 is a longitudinal section through an electrode holder in accordance with the invention, the holder being shown in closed, or electrode-clamping, position;

Fig. 2 is a side elevation, with certain parts broken away, the view showing the holder in open, or electrode-releasing position;

Fig. 3 is a cross section in the plane III—III of Fig. 1; and

Fig. 4 is a cross section in the plane IV—IV of Fig. 1.

As shown in the drawing, the holder comprises a metal frame member 10 formed of sheet metal and being of substantially tubular shape at its forward end 11 and of trough shape at its rear end 12. The extreme rear end portion is tapered down to a narrow tail 13. A bridge member 14 interconnects the two sides of the trough-shaped portion of the frame substantially at the middle thereof, and serves to reinforce a fiber handle 15, which completely encloses the rear half of the frame. The fiber handle 15 is secured to the frame 10 by screws 16.

At the extreme forward end 11 of the frame, the latter is joined to a tubular nose 17, which extends therefrom at an angle. The tubular parts may be joined together by welding, as indicated at 18 in Fig. 2. The electrode-clamping mechanism is contained within the nose 17.

Thus, referring to Fig. 1, an electrode socket 19 is positioned within the nose 17 and supported in electrically insulated relation thereto by a pair of insulating sleeves 20 and 21.

The socket 19 has a longitudinal hole therein dimensioned to receive a welding electrode 22, 55

and the latter is locked in place by a locking pin 23 which extends through an aperture provided therefor in the underside of the socket 19, the bushing 20, and the nose 17. When the tool is in condition for use, the pin 23 is pressed tightly against the electrode 22 to lock it in the socket 19, but the pin is retracted when it is desired to change electrodes.

The mechanism for actuating the pin 23 includes a pair of toggle links 24 and 25, respectively, which are hinged together by a pin 26. When the toggle members 24 and 25 are substantially aligned with each other, as in Fig. 1, the pin 23 is pressed against the electrode 22, and when the toggle links are broken, as shown in Fig. 2, the locking pin 23 is retracted to permit the change of electrodes.

The toggle member 24 has an eye 27 through which the pin 26 passes, and the eye 27 fits between a pair of metal strips 28 (Fig. 3) which comprise the frame of the toggle link 25.

The plates 28 straddle a tongue 29 secured to the frame 10 and projecting through a slot provided therefor in the insulating handle 15, and the plates 28 and the tongue 29 are hinged together by a pin 30, so that when the toggle is broken, as shown in Fig. 2, the member 25 swings about the member 30 as a pivot. To provide a comfortable grip for the operator, the plates 28 are enclosed in a slotted sleeve 31 of insulating material, such as fiber. It may be secured in place by the ends of the pins 26 and 30.

It is desirable to provide for accurate adjustment of the length of the link 24 between the pin 26 and the locking pin 23. To this end, the link 24 includes two members screwed together. Thus the rear member, which is hinged to the pin 26, constitutes a bolt having threads 34 thereon, which screw into threads in a metal sleeve 35, the latter being permanently secured to the locking pin 23. A fiber handle 36 may be provided on the sleeve 35 to facilitate adjustment, since the metal parts adjacent the electrode sometimes get quite hot in service.

The screw thread connection between the members 34 and 35 permits very accurate adjustment of the position of the pin 23 when the tool is in electrode-clamping position, so that the force will always be ample to not only mechanically hold the electrode in the socket, but insure good electrical connection between the electrode and the socket.

In order to insulate the metal members 34, 35 and 28 from the welding electrode, the locking pin 23 is insulatingly supported in the for-

ward end of the sleeve 35. Thus the rear end of the pin 23 and the forward end of the sleeve 35 have a slight taper, and a tapered insulating bushing or sleeve 37 is interposed between the pin and the sleeve. The taper is sufficiently small to insure that the parts will be locked tightly together in response to longitudinal force.

The socket 19 is thoroughly electrically insulated from the nose 17 by the insulating bushings 20 and 21. The bushing 20 is prevented from dropping out of the end of the nose 17 by an insulating washer 38, which is secured in place by a screw cap 39 threaded onto the nose 17.

Current is supplied to the socket 19 through an insulated cable 40, which extends through the hollow handle 15 and is connected to the socket 19 by a connecting element 41. The latter has a tapered end 42 adapted to fit snugly into a tapered hole provided therefor in the upper end of the socket 19. The rear end 43 of the connector 41 is tapered and provided with screw threads for making electrical and physical connection to the stranded wires 44 of the cable 40. Thus the tapered, threaded end 43 is screwed into the stranded core 44, while the latter is supported against spreading by a metal sleeve 45, the sleeve being preferably tapered to increase the wedging action.

The connector 41 is secured to the cable conductor by means of the sleeve 45 before assembly into the tool. Therefore the sleeve 45 is wrapped with a thin, heat-resisting, insulating tape and pushed through the handle 15 until the tapered forward end 42 of the connector 41 is wedged into the tapered hole provided therefor in the socket 19.

To facilitate removal of the tapered pin 42 from the socket 19, apertures 46 are provided in the bushing 20 and the nose 17, in alignment with the connector 41, so that the latter can be dislodged from the socket by means of a punch inserted through the apertures 46.

The tool can be readily adjusted to handle electrodes of smaller diameter than the hole in the socket 19, by turning the adjusting sleeve 36 to vary the length of the forward toggle link 24.

When the tool is in closed position, as shown in Fig. 1, the axis of the pin 26 is slightly above a line connecting the axis of pin 30 with the forward end of the locking pin 23 so that the longitudinal pressure between the electrode and the locking pin tends to retain the link member 24 in closed position. Furthermore, it is retained in this position during use by virtue of the fact that the operator grasps both the handle 15 and the link member 25 in his hand during a welding operation.

To facilitate breaking the toggle connection when it is desired to change electrodes, the handle 31 is extended rearwardly beyond the hinge 30 and the upper side of the rear end of the handle 31 is beveled to permit movement of the link into the open position shown in Fig. 2. By virtue of the fact that the rear portion of the handle 31 extends rearwardly of the pin 30, the operator can snap the toggle links into electrode-releasing position by pressure of the fingers against the rear portion of the handle 31.

To facilitate screwing the connector 41 into the end of the cable, its midportion is flattened as indicated in Fig. 4.

The construction whereby the metal frame of the holder is electrically insulated from the welding circuit has the advantage that the frame can come in contact with the work without drawing

an arc. This enables using the tool with very short electrodes and effects a substantial saving in the number of electrodes necessary.

Although for the purpose of explaining the invention a particular embodiment thereof has been described in detail, it is to be understood that various changes can be made from the exact construction shown, and the invention is, therefore, to be limited only to the extent set forth in the appended claims.

I claim:

1. A device of the type described, comprising a hollow handle adapted to receive an electric cable, frame means extending forwardly from said handle and at least partially enclosing said cable, said frame means having an opening in the extreme forward end thereof for reception of an electrode, an electrode socket within said frame means, electrical insulating means supporting said socket within said frame means and electrically insulating it from said frame means, and means for locking an electrode in said socket.

2. A device as described in claim 1, in which the forward end of said frame means is bent downwardly, whereby an electrode extending from the end thereof extends at a substantial angle to said handle, registering openings in said frame means and said socket on the underside thereof, said means for locking an electrode in said socket comprising a pair of toggle members hinged together, one of said toggle members comprising a locking pin extending through said openings in said frame means and said socket for engaging an electrode in said socket, the other toggle member being pivotally connected to the underside of said handle adjacent the rear end thereof.

3. An electrode handle comprising a channel-shaped, metal frame member, a tubular handle of insulating material enclosing the rear portion of said channel shaped frame member, said channel shaped frame member merging into a tubular section at the forward end, a tubular electrode socket concentrically positioned within the tubular portion of said frame member, insulating sleeve means supporting said electrode socket in said frame member, and insulating it therefrom, registering apertures in the undersides of said socket and insulating sleeve means for entry of a locking pin, a locking pin adapted to be entered through said apertures for clamping an electrode in said socket, and locking means including a sleeve in telescoping relation with the rear end of said locking pin, insulating bushing means interposed between said locking pin and said sleeve for electrically segregating the two elements, and handle means for shifting said sleeve longitudinally to actuate said locking pin.

4. An electrode holder comprising an open-ended, tubular metal frame, a tubular insulating bushing insertable through the open end of said frame, an electrode socket insertable into said tubular bushing through the open end of said frame, an insulating washer insertable into the open end of said frame for retaining said tubular bushing and said socket in place, and a closure member detachably secured to the open end of said frame for maintaining said tubular bushing, said socket and said insulating washer in said frame.

5. An electrode holder comprising a metal frame having a front end from which an electrode is adapted to project, and a rear end from which a current-supply cable is adapted to pro-

ject, an electrode socket insertable into the front end of said frame, means for insulatingly supporting it in said frame, and connecting means adapted to be secured to the end of a cable exterior of said frame and insertable through the rear end of said frame into conducting relation with said socket.

6. An electrode holder as described in claim 5,

in which said socket member has a tapered hole therein and said connector member has a tapered pin portion adapted to be fitted into said tapered hole in said socket to complete electrical connection between said connector and socket.
